UNITED STATES PATENT OFFICE

130,231

DESIGN FOR A PLATE OR SIMILAR ARTICLE

Will Cameron McCartney, Cambridge, Ohio

Application August 26, 1941, Serial No. 103,023

Term of patent 14 years

To all whom it may concern:

Be it known that I, Will Cameron McCartney, a citizen of the United States of America and resident of Cambridge, county of Guernsey, and State of Ohio, have invented a new, original, and ornamental Design for a Plate or Similar Article, of which the following is a specification, reference being had to the accompanying drawing, forming part thereof, in which—

Figure 1 is a top plan view of a plate or similar article, showing my new design; and

I claim:

The ornamental design for a plate or similar article, substantially as shown.

WILL CAMERON McCARTNEY.
